UNITED STATES PATENT OFFICE.

GEORGE P. BRENNER, OF MILWAUKEE, WISCONSIN.

HOLDER AND SPREADER FOR MUCILAGINOUS MATERIAL.

1,170,735.

Specification of Letters Patent.

Patented Feb. 8, 1916.

Application filed November 20, 1914. Serial No. 873,121.

To all whom it may concern:

Be it known that I, GEORGE P. BRENNER, a citizen of the United States, and resident of Milwaukee, in the county of Milwaukee and State of Wisconsin, have invented certain new and useful Improvements in Holders and Spreaders for Mucilaginous Material; and I do hereby declare that the following is a full, clear, and exact description thereof.

My invention consists in what is herein particularly set forth with reference to the accompanying drawings and pointed out in the claims of this specification, its object being to provide simple, economical non-leaking, self-sealing and efficient spreader-holders for mucilaginous material.

Figure 1 of the drawings represents a partly sectional front elevation of a spreader-holder in accordance with my invention having a removable cap covering the discharge and spreading end thereof; Fig. 2, a side elevation of the same partly in section; Fig. 3, a partly sectional view of a fragment of the holder on the plane indicated by line 3-3 in Fig. 4, which Fig. 4 represents a partly sectional front elevation of the same fragment, said Figs. 3 and 4 being upon a larger scale than Figs. 1 and 2, and Fig. 5 is a view illustrating the primarily transverse form of a flexible sealing and spreading strip forming part of said holder.

Referring by numerals to the drawings, 5 indicates a rectangular shell, preferably formed of flexible material and 6 a sealing-plug in screw-thread engagement with a filling aperture with which one end of the shell is provided. The rear of the other end of the shell is necessarily beveled, and it is preferable to bevel the front and sides of said shell at the same end. The front of the shell, at its beveled end is folded, as best shown in Fig. 3, to provide a socket and the inner wall 7 thereof having a central discharge orifice 8 therein, adjacent to its lower end. The orifice is normally sealed by a flexible strip 9 having the upper portion thereof engaging said socket, the fold 10 of the front of the shell is far enough back of the lower edge of said shell to permit of outward yield of said strip, under pressure. The exposed edge of the strip is beveled to be flush with the rear bevel of

the shell below which said strip extends 55 when in normal position to seal the discharge orifice of said shell.

In practice, the shell is held so as to have the lower bevel edge of the sealing-strip 9 therewith contact the material to which 60 mucilaginous contents of said shell are to be applied. As the result of a backward draw of the shell, the sealing-strip 9 is moved away from the orifice 8 of the shell-wall 7 as shown by dotted lines in Fig. 3, 65 and by pressure on said shell some of its contents are caused to be discharged for spreading by said strip. When the spreading operation takes place, the pressure on the shell is sufficiently relaxed to permit return of the free end of the sealing-strip to 70 normal position over the discharge orifice of the shell and drying of mucilaginous material on said strip and shell insures sealing of said orifice.

By having the discharge end of the shell beveled on all sides, it will clear any surface upon which said shell is laid, any side up, and contents from said shell adhering thereto cannot attack said surface.

It is preferable, as herein shown, to provide a suitable removable protective cap 11 for the discharge and spreading end of the shell when said shell is not in use. The cap shown has yielding clamp-sides and it may 85 be readily sprung off and on the shell.

The sealing-strip 9 is removable, and if its working edge becomes too much worn, a new strip may be substituted, said strip being preferably of rubber material and 90 primarily its transverse contour is an arc of a circle, as shown in Fig. 5. By insertion of the strip 9 in the socket provided therefor, it is straightened out against the wall 7 of the shell, and the contractive tendency 95 of its free end insures automatic return of the same to sealing position as soon as opportunity is afforded after having been moved away from said position by manipulation of the spreader-holder as aforesaid.

I claim:

1. A mucilaginous material holder and spreader comprising a flexible shell having a pered filling aperture and a beveled angular discharge end provided with a spreader seat, 105 a wall in said end of the shell provided with a discharge orifice, and a flexible spreading strip normally sealing said orifice, the upper

100

portion of the otherwise free strip being held to said shell against said wall of the same.

2. An adhesive material holder and spreader comprising a flexible shell having a discharge end that is beveled, the material of the shell at the beveled discharge end being folded to provide a doubled outer wall that is parallel and spaced from the beveled surface to form a spreader socket, the outer wall being shorter than the inner wall of the socket, and said inner wall being provided with a discharge opening adjacent the open end of the socket, and a flexible spreader mounted in the socket and normally sealing the discharge opening, the free portion of the spreader projecting beyond the socket.

3. A mucilaginous material holder and spreader comprising a shell having a stoppered filling aperture and an angular end all sides of which are beveled, one side of said end being folded to form a socket and an inner wall having a discharge orifice therein below the open end of the socket,

and a flexible sealing-strip for said orifice, the upper portion of the otherwise free strip being in engagement with said socket.

4. A holder and spreader for adhesive material comprising a receptacle having a flat discharge portion provided with an outlet, the discharge portion above said outlet being provided with a socket, and a spreader formed of a strip of flexible material that is curved on an arc of a circle and has one portion thereof seated in the socket and normally held by its engagement with the socket so that the spreader will be held flat and in position to lie firmly on the flat discharge end of the receptacle to seal the discharge opening therein.

In testimony that I claim the foregoing I have hereunto set my hand at Milwaukee in the county of Milwaukee and State of Wisconsin in the presence of two witnesses.

GEO. P. BRENNER.
